FIG. 1

FIG. 2

FIG. 3

FIG. 4

INVENTOR.
THOMAS S. OGILVIE
BY *B. J. Craig*,
ATTORNEY.

UNITED STATES PATENT OFFICE

THOMAS S. OGILVIE, OF LOS ANGELES, CALIFORNIA

MUSICAL REED

Application filed June 9, 1928. Serial No. 284,052.

This invention relates to improvements in reeds for music instruments.

The general object of this invention is to provide an improved reed which will not absorb moisture and thereupon become unfit upon continued use.

Another object of the invention is to provide a music reed which is coated with a waterproofing material applied to the reed so that the coating does not enter the pores of the reed and thereby destroy the tone qualities of the reed.

An additional object of my invention is to provide a reed having a coating of waterproof material such as soluble celluloid applied thereto.

Other objects and the advantages of this invention will be apparent from the following description taken in connection with the accompanying drawing wherein:

Fig. 1 is a bottom view of a saxophone mouthpiece showing one of my improved reeds operatively positioned thereon.

Fig. 2 is a perspective view of the reed shown in Fig. 1.

Fig. 3 is a greatly enlarged section taken on line 3-3 of Fig. 2, and

Fig. 4 is a perspective view of a double oboe reed.

Referring to the drawing by reference characters I have indicated a reed to which my invention is applied generally at 10 and in Fig. 1 I have shown it as operatively positioned on a saxophone mouthpiece 12 by a clamping member 14.

As shown, the reed 10 is formed in the usual manner and is preferably made of Frejies cane. The reed comprises a body portion 15 tapered at one end as indicated at 16 to form a thin vibratory lip 16.

The reeds now used absorb moisture when played and upon continued use when they become rather moist the multitude of fibers which compose the reed become "waterlogged", thereby destroying the tone of the reed.

My invention consists in coating the reed with a water proofing material 18 as shown in Fig. 3. This water proofing material may consist of a coating of quick-drying celluloid

in acetone, or of a mixture of celluloid, acetic acid, banana oil, and alcohol, either in suitable proportions. Any suitable quick drying liquid which dries to leave a thin somewhat elastic or tough waterproof film will be found suitable.

The waterproofing material 18 is preferably applied to the surface of the reed by spraying. It does not enter the pores of the reed but merely forms an outer film or layer. I prefer to apply the coating layer by layer by spraying on a thin film, then letting it dry, sanding it, recoating and repeating operation as often as desired.

Efforts have been made to make reeds waterproof by dipping them in waterproofing material such as oil, but the material has been found to enter the reed pores and destroy the tone of the reed.

My method of waterproofing musical reeds may be employed on any of the fibrous reeds, whether they be single reed such as the reed 10 or double reeds such as the oboe reed shown in Fig. 4 and indicated at 20.

Any fibrous reed coated with a waterproofing material such as I have described retains its true tone and volume and can be used for a much longer period of time than reeds which are not so treated or which have been dipped.

From the foregoing description it will be apparent that I have provided an improved reed for music instruments which is waterproof, durable and which does not lose its tonal qualities due to the waterproofing.

Having thus described my invention, I claim:—

1. A musical instrument reed comprising a fiber body the surface of which is coated with a thin layer of sprayed celluloid.

2. A fibrous musical instrument reed coated with a thin, flexible, waterproof layer of material including celluloid, said coating being applied to the surface of said reed, the pores of said reed remaining open whereby the tone qualities of the reed are unimpaired.

In testimony whereof, I hereunto affix my signature.

THOMAS S. OGILVIE.
